US00D800160S

(12) **United States Design Patent** (10) **Patent No.:** **US D800,160 S**
(45) **Date of Patent:** **** Oct. 17, 2017**

(54) **DISPLAY SCREEN WITH GRAPHICAL USER INTERFACE**

(71) Applicant: **Microsoft Corporation**, Redmond, WA (US)

(72) Inventor: **Han-Yi Shaw**, Redmond, WA (US)

(73) Assignee: **Microsoft Corporation**, Redmond, WA (US)

(**) Term: **15 Years**

(21) Appl. No.: **29/571,580**

(22) Filed: **Jul. 20, 2016**

CLAIM

The ornamental design for a display screen with graphical user interface, as shown and described.

DESCRIPTION

The FIGURE is a front view of a display screen with graphical user interface showing my new design.

The broken line shown in the FIGURE illustrates the display screen and forms no part of the claimed design.

1 Claim, 1 Drawing Sheet
